PUMPING CONTROL SYSTEM

Harrison B. Hoefer, Milwaukee, Wis.

Application July 14, 1944, Serial No. 544,949

5 Claims. (Cl. 103—40)

1

This invention relates to controls for pumping systems particularly of large capacity such for instance as pumping systems for municipal water works.

Large centrifugal pumps are today quite extensively employed in systems of this type for supplying water against the substantial pressures normally maintained therein. The water from the pump is ordinarily transmitted through a large automatic valve that functions quite satisfactorily under normal operating conditions. But this valve, as heretofore equipped, relies for operation upon the pressure and flow conditions developed by the pump and, in the event of pump failure, cannot be safely depended upon to check the resulting reverse flow or back surge with the promptness required to prevent serious consequences.

An object of the present invention is to provide a more positive control for the automatic valve in systems of this type so as to effect a more reliable operation thereof. This I have accomplished by a control arrangement for the valve involving an element mechanically connected with the pump and directly responsive to the speed of operation thereof.

Other more specific objects and advantages will appear, expressed or implied, from the following description of an illustrative embodiment of the present invention.

In the accompanying drawings:

Figure 1 is a diagrammatic view of a control system embodying the present invention.

Fig. 2 is a sectional view on a larger scale of the governor controlled valve and associated parts included in Fig. 1.

The control system selected for illustration is shown applied to a conventional pumping system, including a large centrifugal pump 10 that supplies water through a large valve 11 into a main 12. The valve 11 is a well known type of rotary valve, commercially known as a "cone" valve, which is actuated and controlled by an hydraulic servo-motor 13 with which such valves are commonly equipped. The piston 14 of the servo-motor is shown connected to the valve actuating lever 15 through which the valve 11 may be rotated into open position from the closed position shown.

In this instance the servo-motor 13 is controlled by a four-way valve 16 which is actuated and controlled by a centrifugal governor 17 driven by the pump 10 through a one-way clutch 18 of any standard or approved type. The servo-motor 13 and consequently the valve 11 are rendered responsive to the speed of the pump 10, the arrangement being such that the valve 11 will promptly close whenever operation of the pump 10 falls below a certain predetermined speed.

The centrifugal governor 17 may assume vari-

2

ous forms. That shown comprises a supporting shaft 19 driven by the one-way clutch 18 and having thereon a pair of axially spaced end heads 20 and 21. Head 20 is fixed to the shaft 19 while head 21 is freely movable axially thereof toward and from the head 20. The heads carry a suitable centrifugal fly-ball arrangement which in this instance comprises a pair of heavy bars 22 each connected to both heads through flexible metallic strips 23. The bars 22 are also interconnected by a pair of parallel tension springs 24 disposed at opposite sides of the shaft 19, each end of each spring being connected to an end of a bar 22 through an appropriate link bolt 25. The springs 24 yieldably resist outward movement of the bars 22 under the centrifugal forces induced by rotation thereof with the shaft 19, inward movement of the bars 22 being limited by suitable adjustable stops, such as screws 26 carried by a collar 27 on the shaft 19.

The arrangement is such that during rotation of the shaft 19, the bars 22 move outwardly and, acting through the strips 23, draw the head 21 lengthwise of the shaft 19 a distance dependent upon the rate of shaft rotation.

This axial movement of the head 21 is utilized to actuate and control the valve 16. In this instance the valve 16 is equipped with an extended valve stem 28 that projects into the adjacent hollow end of the shaft 19. A transverse pin 29 carried by the head 21 and extending through the stem 28 provides a suitable operating connection therebetween, the shaft 19 being longitudinally slotted to accommodate the pin 29 and to permit the same to move with the stem 28 and head 21.

The valve 16 is a four-way valve of a well known type. It includes a longitudinally movable plunger controlled by the stem 28 and having a central head 30 and spaced end heads 31 and 32. The central head 30 controls an annular channel 33 that is continuously supplied with liquid under pressure through a pipe 34. Each of the end heads 31 and 32 controls an annular channel 35, both of which communicate with an exhaust pipe 36. An annular channel 37, disposed between the heads 30 and 31, communicates through a pipe 38 with one end of the servo-motor 13; while another annular channel 39, disposed between the heads 30 and 32 communicates with a pipe 40 that leads to the opposite end of the servo-motor 13. A spring 41 within the hollow end of the shaft 19 acts on the valve stem 28 to urge the valve plunger toward the position shown.

Flow of liquid in one direction through the pipe 40 is normally blocked by an appropriate valve 42. In this instance the valve 42 is urged into the closed position shown by a spring 43 and 60 is equipped with an actuating plunger 44 by

which it may be opened in response to pressure generated by the pump 10. For this purpose the plunger 44 is shown arranged within a cylinder 45 which is exposed to the discharge pressure of the pump 10 through a pipe 46. The valve 42 is preferably by-passed by a connection 47 containing a suitable check valve 48 arranged to permit a free flow of liquid through the pipe 40 in an opposite direction.

The arrangement is such that when the pump 10 is at rest the valve 42 is closed and the plunger of the four-way valve 16 assumes the position shown, in which position the forward end of the servo-motor 13 is exposed to the pressure in the supply pipe 34 through the channels 33 and 37 and pipe 38, and the cone valve 11 is held in closed position. When the pump 10 is energized and attains a predetermined speed, the centrifugal governor 17, driven thereby, functions to shift the plunger of the valve 16 toward the left (Fig. 2) until the central head 30 passes to the left of the supply channel 33, in which position the end head 31 uncovers the adjacent channel 35 so as to open communication between it and the channel 37 and the end head 32 blocks the other channel 35. In this position the forward end of the servo-motor 13 is open to the discharge pipe 36 through the pipe 38 and channels 37 and 35, and the pipe 40 is open to the supply pipe 34 through the channels 39 and 33.

Although the four-way valve 16 has thus been operated in response to a predetermined speed of the pump 10 in a manner to subject the pipe 48 to the pressure in the supply pipe 34, the servo-motor 13 does not function to open the cone valve 11 until the pump 10 has generated a predetermined pressure sufficient to open the valve 42; but when this occurs, the pressure in pipe 40 is then available to promptly actuate the servo-motor 13 in a manner to open the valve 11.

The valve 11 remains open so long as the speed of the pump 10 remains above a predetermined minimum, but with any decrease in speed, the governor 17 forces the plunger of the valve 16 toward the position shown, and the instant that the pump speed falls below that minimum the central head 30 of the valve 16 opens the supply channel 33 to the channel 37 to thereby direct fluid pressure into the pipe 38 and to thus energize the servo-motor 13 in a direction to close the cone valve 11. During this valve closing action of the servo-motor, the liquid discharged therefrom is free to flow through the pipe 40 and check valve 48 to and through the valve channels 39 and 35 to the exhaust pipe 36. It will be noted that the check valve 48 insures a free discharge of liquid from the servo-motor so as not to interfere with its valve closing action, even though the valve 42 may have closed as a result of a drop in pump pressure.

A control system has thus been provided which functions to maintain the main valve 11 open only while the pump 10 is functioning normally and at a speed above a predetermined value and by which the valve 11 is promptly closed whenever the pump speed falls below that value, so as to effectively block the flow in the main 12 long before a reverse flow or back surge can develop therein as a result of pump failure. Should the pump in starting fail to develop a normal pressure, as a result of priming failure or otherwise, the control system shown will function to hold the valve 11 closed, the valve 42 being provided for that purpose.

It will be also noted that by reason of the fact 75

that the governor 17 is driven from the pump 10 through a one-way clutch 18, the governor 17 will come to rest or remain at rest, and consequently the valve 11 will close or remain closed, should the pump 10 at any time operate in reverse.

Various changes may be made in the embodiment of the invention hereinabove specifically described without departing from or sacrificing the advantages of the invention as defined in the appended claims.

I claim:

1. In a pumping system the combination of a conduit, a pump for supplying liquid to said conduit, a valve for controlling communication between said pump and conduit, a servo-motor alternatively operable to open and close said valve, and speed responsive means including a centrifugal governor driven by said pump and a four-way valve actuated by said governor for rendering said servo-motor operable to open or to close said valve whereby said valve is maintained in open condition only when said pump is operating at speeds above a predetermined minimum.

2. In a pumping system the combination of a conduit, a pump for supplying liquid to said conduit, a valve for controlling communication between said pump and conduit, a servo-motor alternatively operable to open and to close said valve, a four-way valve for controlling said servo-motor, and a centrifugal governor driven by said pump and mechanically connected to said last named valve to control the latter.

3. In a pumping system the combination of a conduit, a pump for supplying liquid to said conduit, a valve for controlling communication between said pump and conduit, a servo-motor alternatively operable to open and to close said valve, a four-way valve for controlling said servo-motor, and a centrifugal governor driven by said pump and operable on said last named valve to actuate the same.

4. In a pumping system the combination of a conduit, a pump for supplying liquid thereto, a valve for controlling communication between said pump and conduit, a servo-motor alternatively operable to open and to close said valve, means including a centrifugal governor for controlling said servo-motor, and a one-way clutch through which said governor is driven by said pump.

5. In a pumping system the combination of a conduit, a pump for supplying liquid to said conduit, a valve for controlling communication between said pump and conduit, means including a centrifugal governor responsive to the speed of said pump for opening said valve at a predetermined pump speed and for closing said valve at pump speeds below said predetermined speed, and pressure responsive means for preventing opening of said valve when pump pressures are below a predetermined minimum.
